UNITED STATES PATENT OFFICE.

MAURICE TOBIN, OF MARION, OHIO.

REPAIR LINK.

1,412,724.

Specification of Letters Patent. Patented Apr. 11, 1922.

Application filed June 13, 1921. Serial No. 477,116.

To all whom it may concern:

Be it known that MAURICE TOBIN, a citizen of the United States, residing at Marion, in the county of Marion and State of Ohio, 5 has invented certain new and useful Improvements in Repair Links, of which the following is a specification.

The present invention relates to repair links for chains of various sizes, and has 10 for an object the providing of a relatively strong and durable link which may be easily and quickly substituted for a broken or worn link at any part of a chain throughout its length. 15 Another object of the invention is to provide a link, the body portion of which may be constructed in one piece of substantially the same diameter throughout its length so that the body portion may be made from a 20 length of stock material of a diameter equal to that of the finished link so that time and material are saved as it is unnecessary to work down the major portion of the link to leave outstanding parts as has been the 25 case with a large number of prior devices. The invention further aims at the provision of a link having a body portion which extends around the ends of the link and presents an integral structure whereby the full 30 strength of the material is had and whereby no undue strain or stresses are imposed upon the detachable section which is used for closing the side of the link.

A further object of the invention is to 35 provide a link open at one side only and which has its spaced end portions similarly constructed for receiving therein a closure portion which is similarly constructed at opposite ends, thus avoiding the necessity 40 of delay and accuracy in properly matching the ends of the insertable portion with the ends of the link body.

A still further object of the invention is to provide an insertable member constructed 45 with locking pins as a part thereof adapted to engage the end portions of the body of the link and to provide the body of the link with receiving portions for the pins whereby the insertable section only is provided 50 with projecting parts, thus simplifying the construction of the body portion of the link and reducing the cost of manufacture.

The above and various other objects and advantages of this invention will in part be 55 described in and in part be understood from the following detailed description of the

present preferred embodiment, the same being illustrated in the accompanying drawing, wherein:

Fig. 1 is a plan view of a link constructed 60 according to the present invention, the same being incorporated in a section of a chain.

Fig. 2 is an enlarged plan view of the body portion of the link having the insertable section removed therefrom. 65

Fig. 3 is a similar view of the insertable section detached from the body portion of the link.

Fig. 4 is a longitudinal section taken 70 through the open side of the link with the insertable section secured therein, the section being taken along the line 4-4 of Fig. 1, and

Fig. 5 is an edge elevation of the open 75 side of the link showing the insertable section therein, and ready to be swung into an interlocked position.

Referring to the drawing, 10 designates the links of a chain which may be of any approved type or construction and with 80 which the link of this invention may interfit. The repair link of this invention comprises a body portion 11 made from a length of stock material of desired diameter and suitable length and which has its end portions 85 rolled or bent over to form hooks 12 which provide end portions for the link body. The extremities of the hooks 12 terminate in spaced relation and opposite each other at one side of the link to form a gap or opening 13. The ends of the hooks 12 are of like construction, and, as shown to advantage in Figs. 2 and 5, the same are recessed at opposite sides as at 14, and the wall of the recess is sloped or inclined from the shoulder 95 15 of the recess to the extremity of the hook 12 thus providing a tapering seat 16. The wall of the recess 14 is transversely flat and is provided intermediately in the face thereof with a depression 17 of substantially semi-spherical contour and which terminates at its forward end in an abrupt shoulder 18, the same continuing beyond the plane of the flat wall 14 and forming the inner end of a complementally formed lug 19. The extremity of 100 the hook 12, at the end of the seat 16, is provided with a transverse groove 20 which is concave from the inner to the outer wall of the seat 16, and which terminates in a forwardly projecting portion 21 of the hook, 110 providing a lip. The concave groove 20 of the ends 12 are so arranged as to form arcs

of a circle whose center lies between the spaced apart ends 12 and the axis of which is coincident with the axis upon which turns an insertable closure member 22 arranged to 5 close the gap 13 in the link. This insertable member 22 is provided with an enlarged middle portion corresponding in diameter substantially to that of the ends 12 and which is cut away at opposite sides and opposite 10 ends to form like end tongues 23 which taper toward their outer ends and are complementary to the seats 16 for forming therewith continuations of the exterior cylindrical surface of the body of the link. The tongues 15 23 are provided with the depressions 17 and the lugs 19 in a manner similar to the formation of the ends 12 of the body of the link so that the tongues 23 and the seats 16 interfit and interlock when the insertable section 22 20 is swung into place.

For the purpose of rigidly securing the insertable section in the gap 13, the lugs 18 of the section 22 are provided with outstanding rivet pins 24 which are adapted to enter 25 openings 25 formed in the bottoms of the depressions 17 of the ends 12. From Fig. 2 it will be noted that the openings 25 have countersinks 26 in their outer ends and into which may be swaged or upset the ends of 30 the pins 25 for riveting the parts together.

In the manufacture of the link the depressions and lugs 17 and 18 are similarly formed in all four interfitting parts and the only differences in the formation of the ends of 35 the body 11 and the removable section 22 is in the provision of the lips 21 on the body section 10 and the formation of the diagonal end faces or shoulders 27 on the removable section 22.

40 In assembling the link it is only necessary to lift out the removable section 22 and engage the ends or hooks 12 of the body portion through the adjacent links 10 of a chain. The section 22 is now inserted in the gap 13 45 in the diagonal position shown in Fig. 5 with the tongues 23 extending above and below the seats 16 and facing the latter. The section 22 is now turned to swing the tongues 23 down upon the seats 16 and the pins 24 projecting into the openings 25 while the lugs 19 of the tongues and seats move behind each other and into the opposite depressions 17. The shoulders 18 are thus relatively deep and provide a substantial resistance to the drawing out of the ends 12 of 50 the link when the latter is subjected to abnormal strain.

It is of course understood that various changes and modifications may be made in 60 the details of construction and design of the above specifically described embodiment of this invention without departing from the spirit thereof, such changes and modifications being restricted only by the scope of the 65 following claims.

What is claimed is:

1. A repair link comprising a body portion interrupted at one side to form a gap thereat and having locking ends facing in opposite directions, and an insertable section adapted 70 to be fitted crosswise in the gap between said ends of the body portion and having complementary locking ends facing in opposite directions, whereby the locking ends of the body portion and the insertable section may 75 be interlocked upon the axial turning of the latter on an axis intersecting the gap between the ends of the body portion.

2. A detachable link for chains, comprising 80 a body section having a gap at one side, an insertable section arranged to fit in the gap, said body section and said insertable section having complementary seats and tongues adapted to be brought together upon the swinging of the insertable section in said 85 gap, said seats and tongues having depressions therein and lugs projecting therefrom in complementary relation to the depressions whereby the lugs are adapted to interfit with said depressions upon the closing of the 90 tongues on the seats.

3. A repair link for chains comprising a length of stock material bent at opposite ends to form a body section open at one side and having its ends reduced in thickness and 95 similarly formed with depressions and projections, and an insertable section arranged to fit between the ends of the body portion and having similarly formed extremities provided with depressions and projections arranged complementary to the depressions and 100 projections of the body portion, said insertable section being adapted to be turned in the gap for interlocking the projections in the depressions and closing the open side of 105 the link.

4. A repair link comprising a body portion curved to provide end hooks and a gap at one side, an insertable section arranged to fit in the gap, the ends of the body portion and 110 the ends of the insertable section being similarly formed with depressions and lugs and being adapted for interlocking engagement upon the turning of the insertable section in the gap and means carried by the insertable 115 section for securing the same in interlocking position in the gap.

5. A repair link for chains comprising a body portion formed of a single length of stock material having its ends rolled over to 120 provide hooks adapted to engage through adjacent links in a chain, the ends of said body portion being similarly formed and each being reduced to provide a seat and having a depression in the wall of the seat and an 125 outstanding lug at the outer end of the depression projecting from said wall, and an insertable section adapted to be positioned between the ends of said body portion, said insertable section having its ends reduced 130

and provided with depressions and projections complementary to the projections and depressions of the ends of the body portion, the projections of the said insertable section having outstanding rivet pins thereon and said ends of the body portion having openings in the bottoms of the depressions thereof for re-

ceiving said rivet pins, said rivet pins being adapted to be swaged at their outer ends securing the insertable section in the body section. 10

In testimony whereof I affix my signature.

MAURICE TOBIN.
